UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

TRUCK SIDE FRAME.

Application filed July 10, 1922. Serial No. 572,992.

To all whom it may concern:

Be it known that I, JOHN A. LAMONT, a citizen of the United States, residing at Chicago, in the county of Cook and State of Illinois, have invented certain new and useful Improvements in Truck Side Frames, of which the following is a specification.

This invention relates to railway car truck side frames, and particularly those of the 10 six-wheel type.

When a side frame is cast in a single piece, the pedestal jaws and brake hanger brackets form enlarged ends which are gripped by the mold so that shrinking, during the cooling of the casting in the mold, is not uniform. As a result thereof trouble is sometimes experienced in that cracks are developed in those portions of the casting intermediate of the jaws.

One object of the invention is to overcome any tendency there may be for the side frame to crack at such portions.

Another object is to provide a simple and durable side frame having a maximum amount of strength without an increase in weight of material.

Another object is to provide a side frame adapted to meet the various requirements under service conditions.

These and other objects are accomplished by means of the arrangements disclosed on the accompanying sheets of drawings, in which—

Figure 1 is a top plan view of a truck side frame embodying my invention;

Figure 2 is a side elevation of the same side frame;

Figure 3 is a side elevation of the main portion of the side frame;

Figure 4 is a side elevation of one end of the side frame, including a brake hanger bracket and pedestal jaws;

Figure 5 is a sectional view taken in the plane of line 5—5 of Figure 1;

Figure 6 is a sectional view taken in the plane of line 6—6 of Figure 1;

Figure 7 is a top plan view of a modification of my invention;

Figure 8 is a side elevation of the arrangement shown in Figure 7;

Figure 9 is a side elevation of the main part of the side frame shown in Figure 8;

Figure 10 is a side elevation of the brake

hanger bracket and pedestal jaws forming one end of the truck side frame;

Figure 11 is a side elevation of a bracket which cooperates with the piece shown in Figure 10 to form a bolster opening and support;

Figure 12 is a sectional view taken in the 60 plane of line 12—12 of Figure 7;

Figure 13 is a sectional view taken in the plane of line 13—13 of Figure 7;

Figure 14 is a sectional view similar to that shown in Figure 12 and showing a further modification which is one of the preferred embodiments;

Figure 15 is a section showing the form which the main channel portion shown in Figure 9 may take if desired; this also being one of the preferred embodiments.

The various novel features of my invention will be apparent from the following description and drawings and will be particularly pointed out in the appended claims.

Referring first to Figures 1 to 6 inclusive, it will be noted that the side frame is made up of three cast pieces, a main central side frame member 10 and two end side frame members 11. The central member 10 is provided with two downwardly extending bracket portions 12 each of which forms one wall of a bolster opening, the other wall in each case being formed by the inner shoulder 13 on the separate end members 11. The section of the main frame member 10 is channel shaped as shown particularly in Figure 6. The downwardly extending side walls 14 of the side frame member 10 are provided with openings 15 for the reception of pins upon which equalizers, not shown, are pivotally supported. As shown particularly in Figure 1, the side walls 14 converge toward the end of the frame member and terminate in spaced wall portions 16 which are a relatively small distance apart and are provided with a plurality of rivet holes 17.

Adapted to be received between such side wall members 16 is a web 18 formed on the end member or combined 95 brake hanger bracket and jaw member 11. This web 18 also is provided with rivet holes 19 which register with the openings 17 and through which rivets may be passed for securely holding the end pieces 11 and main 100 side member 10 together. In this same com-

nection the lugs 20 depending from the main frame member 10 are provided with rivet holes 21. The side wall 22 at the inner end of each member 11 is also provided with rivet holes 23 which register with the rivet holes 21.

In this arrangement in which the end portions, including the brake hanger brackets 9 and the pedestal jaws 24 are separate from the main central side frame member 10, a division is made at a section practically over the point of support or jaws 24 where the stress in the casting under the working load is purely shear. By the arrangement of rivets above and below the parting line and on either side of the point of support, as shown, their maximum value is obtained in forming a rivet connection of this part.

It is proposed to drill the holes 15 in the main frame member 10 and the holes 25 in the end pieces 11 for the pins supporting the outer ends of equalizing levers after the parts 10 and 11 are riveted together, and by reason of projecting lugs 20 on the middle portion, the pins also form a connection between the members 10 and 11 so that the load is transmitted thereby directly to the middle portion of the frame and does not go directly on the rivets. All of the rivets are arranged so that they are accessible for driving by a machine compression riveter, and the side walls 16 and web 18 of the separate parts by reason of the U-shape, are free to be drawn to place against the corresponding portions of the other parts through pressure of the riveting machine.

Construction of the parts also permits of the necessary longitudinal adjustment of the end pieces 11 relative to the main central frame piece 10, in order to bring the distance between the outer axles or from center to center of the jaws 24 exactly to drawing dimensions, thus avoiding the necessity of machining the inner surfaces of the jaws 24, which finishing is required in the integral or one piece construction in order to correct a wide variation in shrinkage of individual castings. The rivet holes 17 in the main piece 10 are cored and after the end members 11 and main central piece 10 are assembled, bringing the distance between the center of the outer jaws to an exact dimension, the holes 19 in the end pieces 18 will be drilled, and after the riveting is completed the alined pin holes 15 and 25 will be drilled to exact distance relative to the center line of the truck.

This three piece construction can be made without any appreciable increase in weight over the single piece, as the end pieces, as well as the middle piece, by reason of their reduced length, can be cast with thinner sections than is possible with the integral casting and more than is required for strength.

65 This reduction in thickness will fully com-

pensate for the extra weight due to overlapping of the parts to secure a riveted connection.

Referring now to Figures 7 to 13 inclusive, it will be noted that instead of using the cast metal middle piece 10, I have provided a rolled metal piece 26 of channel section, best shown in Figures 12 and 13. The end pieces 27 are secured to the middle piece 26 by rivets 28 on three sides, it being noted by reference to Figures 12 and 13 that the section of the end pieces 27 along the lines 12-12 and 13-13 of Figure 7, are U-shaped and fit up within the middle piece 26. Each end piece 27 is provided with openings 29 for the reception of fulcrum pins for the equalizing levers. Separate brackets 30 are secured to the middle piece 26 cooperating to form bolster openings 31.

In Figure 14 there is shown a section similar to that shown in Figure 12 but using standard bulb angle iron in place of the special section shown in Figure 12, the parts 30' and 31' being riveted together in substantially the same way as shown in Figure 12.

In Figure 15 there is shown in section a modified middle piece 32 somewhat similar to that shown in Figure 9, but in this case the lower edges of the U-shaped section are bulb shaped. This section is rolled flat and in a separate operation pressed or rolled to channel shape. The re-entering flanges or bulbs shown in Figures 14 and 15 have the advantage of relieving rivets which secure the end castings to the main side frame piece of a large percentage of the shearing stresses. It will be understood, in assembling the end pieces and the main central piece having bulb portions at lower ends of the side flanges, as shown in Figures 14 and 15, that the end pieces will be slid in endwise to obviate the necessity of spreading outwardly the side flanges of the main central piece.

110 It is my intention to cover all modifications of the invention falling within the spirit and scope of the following claims.

I claim:

1. In a six-wheel truck, a side frame comprising a main central piece having depending projecting portions, and separate end pieces having portions complementary to said depending projecting portions and being secured to said main piece at points where the working load is purely shear.

2. In a six-wheel truck, a side frame comprising a main central piece having depending projecting portions, and separate end pieces having portions complementary to said depending projecting portions, and being secured to said main piece at points where the working load is purely shear, each end piece including a brake hanger bracket and journal box jaws.

3. In a six-wheel truck, a side frame comprising a main body having depending portions each forming a side wall of a bolster opening, and a plurality of end pieces secured to said main body, each end piece including a brake hanger bracket, pedestal jaws and a wall portion cooperating with the depending portions of said main body to complete the bolster openings.
- 5 4. In a six-wheel truck, a side frame comprising a main body piece having vertical flanges, and end pieces each having a single web which extends upwardly between and engages said flanges and is secured thereto for completing the side frame, said end pieces each including a brake hanger bracket and journal box jaws.
- 10 5. In a six-wheel truck, a side frame comprising a main body piece having vertical flanges, and end pieces secured to said main body piece, each end piece including a brake hanger bracket and pedestal jaws, said vertical flanges and end pieces having aligned openings for the reception of equalizer pivot pins.

Signed at Chicago, Illinois, this 6th day of July, 1922.

JOHN A. LAMONT.
